UNITED STATES PATENT OFFICE.

FRANK MESKER, OF ST. LOUIS, MISSOURI, ASSIGNOR TO MESKER & BROTHER,
OF SAME PLACE.

PLATE-METAL COLUMN.

SPECIFICATION forming part of Letters Patent No. 397,868, dated February 12, 1889.

Application filed November 27, 1888. Serial No. 292,026. (No model.)

To all whom it may concern:

Be it known that I, FRANK MESKER, of St. Louis, Missouri, have made a new and useful Improvement in Plate-Metal Columns, of 5 which the following is a full, clear, and exact description.

The improvement relates, mainly, to a class of construction employed in architectural work, such as building fronts.

10 It consists, mainly, in the special shape imparted to the single plate which composes the front and sides of the column, substantially as is hereinafter set forth and claimed, aided by the annexed drawings, making part of this 15 specification, in which—

Figure 1 is a view in perspective of the improved column and having ornamental portions applied thereto; and Fig. 2, a horizontal section, upon an enlarged scale, of the column.

20 The same letters of reference denote the same parts.

A represents the metal plate which forms the front *a* and the sides *a'* *a'* of the column.

B represents a wooden piece inserted within 25 the sides *a'* *a'*. It is fastened to the plate A, and preferably by means of such fastenings as the screws C. The piece B forms the back of the column, and it is also made to largely occupy the interior of the column, and thereby 30 serve to brace the sides *a'* *a'* throughout the principal portion of their width, as well as to strengthen the column generally. The principal feature, however, of the column, and which is of value irrespective of the thickness 35 of the piece B, is the special shape imparted to the front portion of the plate A. In the place of shaping the plate to form square corners at the front of the column, it is shaped to form round corners, substantially as is 40 shown at *a* *a*—that is, in a column, say, six inches wide by six inches deep the corners *a* *a* form a quarter-turn whose radius is one and one-half inch.

45 From this construction several advantages accrue. The demands of the trade require a

column of the kind under consideration to be sold at a rate that necessitates the use of a comparatively brittle metal, and to enable such a grade of metal to be used successfully I have discovered that sharp angles in it must 50 be avoided, and that rounded turns—such as at the corners *a* *a*—must be employed, for the fiber of the metal extends upward and downward in the column, and when the plate is bent parallel with the direction of the fiber 55 it cracks and becomes useless. This difficulty is avoided in the manner described. The rounded corner is also desirable, in that it is stronger generally than the square corner, and in that it is better protected from injury. 60 The column also is better suited for many architectural designs than is one having square corners. Ornamental parts—such as the capital D and base E—can be applied to the plate A, and can be secured thereto by 65 any suitable means. It is desirable that these parts be made to fit the rounded corners *a* *a*, substantially as is shown in Fig. 1.

I claim—

1. The herein-described plate-metal column, the same consisting of the single plate A and the piece B, said plate forming the front and the sides of the column, and being shaped to form the rounded corners *a* *a*. 70

2. The herein-described plate-metal column, the same consisting of the single plate A and the piece B, said plate being shaped to form the front and sides and rounded corners, as described, and said piece B being made to form the back of the column and to 75 occupy the principal portion of the interior of the column, and being united to the column-sides, as set forth. 80

Witness my hand this 19th day of October, 1888.

FRANK MESKER.
